UNITED STATES PATENT OFFICE.

CHARLES B. GARRETT, OF MINNEAPOLIS, MINNESOTA.

AUTOMATIC SPRINKLER-HEAD.

1,013,545.

Specification of Letters Patent.

Patented Jan. 2, 1912.

Application filed February 17, 1909. Serial No. 478,452.

To all whom it may concern:

Be it known that I, CHARLES B. GARRETT, a citizen of the United States, residing at Minneapolis, in the county of Hennepin and State of Minnesota, have invented certain new and useful Improvements in Automatic Sprinkler-Heads; and I do hereby declare the following to be a full, clear, and exact description of the invention, such as 10 will enable others skilled in the art to which it appertains to make and use the same.

My present invention has for its object to provide an improved sprinkler head for use in connection with automatic fire extinguisher systems, and generally stated, has for its objects, to provide a sprinkler head of greater reliability, durability and efficiency.

Particularly, this invention has for its object to improve sprinkler heads of the type disclosed and claimed in my prior Patent No. 758,522, of date April 26, 1904, and No. 777,783, of date December 20, 1904.

To the above ends, the invention consists 25 of the novel devices and combinations of devices hereinafter described and defined in the claims.

In the accompanying drawings which illustrate the improved sprinkler, like characters indicate like parts throughout the several views.

Referring to the drawings: Figure 1 is a view in front elevation, showing the improved sprinkler head; Fig. 2 is a vertical section taken on the line $x^2 x^2$ of Fig. 1; Fig. 3 is a horizontal section taken on the line $x^3 x^3$ of Fig. 2; Fig. 4 is an elevation, showing the cap and compression block of the sprinkler head removed from working 35 position; Fig. 5 is a plan view of the cap; Fig. 6 is a plan view, showing a copper gasket which forms a part of the cap; Fig. 7 is a section taken on the line $x^7 x^7$ of Fig. 6; Fig. 8 is a plan view of the compression 40 tank; Fig. 9 is a section taken on the line $x^9 x^9$ of Fig. 8; Fig. 10 is a side elevation, showing the compression member of a so-called toggle acting strut; Fig. 11 is a front elevation of the said compression member; Fig. 12 is a front elevation of the lever member of the toggle acting strut; Fig. 13 is a side elevation of the said lever, some parts being broken away; Fig. 14 is a front elevation of a detachable section of the strut 45 lever; Fig. 15 is a side elevation of the same; Fig. 16 is a view corresponding to

Fig. 12, but showing a slightly modified construction; Fig. 17 is a view corresponding to Fig. 11, but showing a slightly modified form of the compression member of the 60 strut, some parts being broken away; Fig. 18 is a front elevation corresponding to Fig. 14, but showing a slightly modified form of the detachable member of the strut lever; Fig. 19 is a plan view, showing a modified 65 form of the strut locking device; and Fig. 20 is a view partly in side elevation and partly in vertical section, showing a still further modified form of the strut locking device applied to the compression and lever 70 members of the strut.

In the drawings, the numeral 1 indicates a nozzle which is adapted to be secured in the usual way to the pipe fitting of the fire extinguisher installation. The upper end 75 of this nozzle 1 terminates in a raised annular cap seat or flange 2, and is further provided with a yoke or arch 3 that supports at its upper portion, a hub or nut block 4. An abutment screw 5 which will be further 80 described later on, is screwed axially through the hub 4 and projects below the same. A spraying head 6 is secured on the upper portion of the hub 4 and projects beyond the same.

The orifice or water discharge passage in the cap seat 2 is normally closed by a cap 7, preferably of bronze, between which and said seat, a thin copper gasket 8 is interposed. The said cap 7 and gasket 8 are preferably centered by a plurality of cooperating depressions 9, and the said cap is preferably formed with an axial upwardly extended knob 10, that engages an axial seat of the so called compression block 11, 95 preferably made of copper and provided with diametrically opposite pairs of laterally spaced lugs 12. The said parts 7, 8 and 11 are held together and the gasket 8 is tightly pressed onto the sharp upper 100 edge of the cap seat 2, by a toggle acting strut of novel construction, several forms of which are illustrated in the drawings. For convenience in description, this toggle acting strut may be said to be made up of a 105 compression member, a lever and a lock device, one of which members has parts connected by solder of proper fusibility. The compression member 13 of the strut, at its extreme lower end, is seated on the compression block 11 between the lugs 12 thereof, and it is stiffened by a longitudinally

extended corrugation 13^a, that terminates preferably slightly above its extreme lower end. At its upper end, the said compression member 13 is formed with spring prongs 13^b 5 that are bent laterally away from its intermediate upper end portion 13^c. The said bearing end 13^a and the ends of the spring prongs 13^b engage a slightly curved, nearly flat seat 14, formed in the bend of the lever 15, which lever, in its short upper end which 10 overlies and projects beyond the upper end of said compression member 13, is provided with a depression or seat 15^a in which the lower end of the abutment screw 5 is seated. Approximately the upper half portion of this lever 15 is slightly flexible, while the lower half section thereof is made inflexible by a central longitudinally extended corrugation 15^b. To this inflexible portion 15 of the lever 15, a detachable section 16 is secured by solder 17. The lower end of this detachable section 16 is preferably bent to form a hook 16^a. The lever 15, at the junction of its flexible and inflexible portions, 20 is further stiffened by an arched rib 15^c. The strut lock, in this construction, is made up of a wire yoke 18 having eyes 18^a at the ends of its prongs, and a lock rod 19 having crooked or laterally bent ends. When the 25 lock is applied, the yoke 18 embraces the lower end portions of the compression member 13 of the strut, and the rod 19 is passed through the eyes 18^a and seated in the hook 16^a of the detachable lever section 16. It 30 may be here stated that this section 16 really forms a part of the strut locking device, for when the solder 17 is melted, it separates from the lever 15 and permits the strut to buckle and fly to pieces, thereby 35 releasing the cap 7.

As best shown in Figs. 14 and 15, the section 16 is provided with laterally spaced flanges 16^b that are adapted to embrace the sides of the rigid or inflexible part of the 40 lever 15.

Fig. 16 shows a lever which is like that illustrated in Figs. 1, 2, 12 and 13, except that it is provided with outwardly extended perforated ears 15^d, through which the 45 flanges 16^b of the detachable section 16 are adapted to be passed.

The assembled strut is put under the desired pressure by tightening the abutment screw 5 until the parts 7, 8 and 11 are properly seated (see Fig. 2), and then the outer end of said screw is cut off close to the upper end of the hub 4. To secure the abutment screw when it is properly set as above stated, a pin 19 is preferably driven through 50 coincident perforations in the said screw and in the hub 4.

To solidify the strut after it has been properly assembled, a small screw 20 is screwed through a threaded seat 21 in the 55 compression member 13, until its inner end

impinges against the inflexible end of the lever 15. Then the outer end of said screw 20 is preferably cut off, and the said screw secured to the said member 13 by solder indicated at 21^a.

In Fig. 17, the compression member 13 of the strut is shown as provided with a vertically elongated slot 22, and in Fig. 18, the section 16 is shown as provided with a hooked end 16^c.

Fig. 19 shows a lock plate 23, which at one end, is provided with a transverse slot 24, and at its other end, is formed with a flat head 25 connected to said plate by a narrow neck portion 26. This device shown in Fig. 19, is adapted to take the place of the yoke 18 and lock rod 19. It is applied by inserting the flat head 25 thereof through the slot 22 of the compression member 13; then turning the said plate 23 into a horizontal position; and then inserting the hook 16^c of the member 16 through the slot 24 thereof.

The construction illustrated in Fig. 20 is like that illustrated in Figs. 17, 18 and 19, except that the strut lever 27 is provided with a hook like lower end 28 adapted to be inserted through the slot 24 of the lock plate 23, and the said lock plate is made up of two sections connected by solder 29, shown as applied between interlapped transversely 95 bent portions thereof.

With the lock plate construction shown in Figs. 17 to 20 inclusive, the shoulders, at the junction of the neck 26 with the body of the neck plate, serve to solidify the strut structure without the use of the screw 20.

By forming the strut lever with the inflexible section where the solder is applied between the same and the detachable section 16, separation of the soldered members by a peeling action which will be produced by flexibility at such place, is prevented. It should also be noted, see particularly Figs. 2 and 18, that the depression 15^a in the lever 15 in which the depending end of the abutment screw 5 is seated, forms a boss on the under side of the upper end of the lever, and affords a stop which prevents outward movement of the upper end of the compression member or strut proper 13 and thus holds the said compression member properly seated in the bearing surface or seat 14 of the said lever. This boss also fits in the corrugation of the compression member 13, thereby centering the said members 13 and 15 and aiding in the proper assembling of the strut members. Furthermore, said boss permits the upper end of the compression member 13 to be seated on a comparatively flat portion of the lever, and making unnecessary an abrupt bend in the said lever, such as would tend to weaken the same.

The valve, or cap, as it is usually termed by those versed in the art, is the most radi- 130

cal departure from previous forms. It is designed to improve the tightness of the joint, thereby preventing leakage of water or air. Means for the adjustment of the strut structure on an elastic base become necessary if leakage was to be prevented, and the form here shown, consisting of the soft copper compression block riding on the spring hard cap, and registering with it and the soft copper gasket, affords means for adjusting in a partially assembled form, and when complete closing is effected, an "ironing" movement is produced on the gasket by the spring hard cap, that improves the joint to a great degree. When closed completely, the compression block and the cap become an inelastic unit.

What I claim is:

1. In an automatic sprinkler, a strut structure having a member formed with flexible and reinforced inflexible portions.
2. In an automatic sprinkler, a strut structure having a lever formed with flexible and reinforced inflexible portions, and with a releasing member soldered to said inflexible portion.
3. In an automatic sprinkler, a toggle acting strut comprising a compression member, a lever having flexible and reinforced inflexible portions, and a strut locking means including a section secured by solder to the inflexible portion of said lever.
4. In an automatic sprinkler, the combination with a cap normally closing the discharge orifice thereof, of an abutment overlying said cap, a lever seated against said abutment, a compression strut seated against said cap and said lever, fusible locking means connecting said lever and compression strut, and a screw applied to said compression strut, engaging said lever, and solidifying the strut structure.
5. In an automatic sprinkler, the combination with a cap normally closing the discharge orifice thereof, an abutment overlying said cap, and a toggle acting strut comprising a longitudinally corrugated compression member seated on said cap, a lever intermediately seated on said compression member and reacting against said abutment,

said lever having a corrugated inflexible lower end section, a plate or lever section secured to the inflexible portion of said lever by fusible solder, and a locking device connecting said plate or lever section to said compression member.

6. In an automatic sprinkler, the combination with a cap normally closing the discharge orifice thereof, and an abutment overlying said cap, of a toggle acting strut comprising a compression member seated on said cap, a lever seated on said compression member, provided at its upper end with a depressed seat for said abutment, and formed at its depending portion with a longitudinal corrugation and with an arched rib extending transversely of the upper end of said corrugation, and fusible locking means connecting the inflexible lower portion of said lever to the lower portion of said compression member.

7. In an automatic sprinkler, a strut structure comprising a compression strut, a lever fulcrumed thereon, and fusible locking means associated therewith, said lever having flexible and reinforced inflexible portions.

8. In an automatic sprinkler, a toggle acting strut, including fusible strut locking means, and a thrust screw incorporated in one of the members for solidifying said strut until released by heat.

9. In an automatic sprinkler, a cap normally closing the discharge orifice thereof, an abutment overlying said cap, a strut structure including a fusible member reacting against said abutment and said cap, said cap comprising a copper gasket, a copper compression block and an intermediate member of relatively hard metal, the said compression block being sprung and pressed against the said intermediate member, substantially as described.

In testimony whereof I affix my signature in presence of two witnesses.

CHARLES B. GARRETT.
